United States Patent Office

Des. 178,652
Patented Sept. 4, 1956

178,652

RUBBISH BURNER

Leland A. Dunkelberger, Battle Creek, Mich.

Application November 1, 1954, Serial No. 32,892

Term of patent 14 years

(Cl. D81—1)

— F 1 — 1 —

I claim:

The ornamental design for a rubbish burner, substantially as shown.
